UNITED STATES PATENT OFFICE.

ALBERT H. TAFT, OF WINCHESTER, NEW HAMPSHIRE.

WAGON-JACK.

SPECIFICATION forming part of Letters Patent No. 288,275, dated November 13, 1883.

Application filed January 8, 1883. (No model.)

To all whom it may concern:

Be it known that I, ALBERT H. TAFT, of 5
Winchester, in the county of Cheshire and
State of New Hampshire, have invented a new
and useful machine for lifting wagons, buggies,
and all other wheel-carriages, to be known as
the Improved Wagon-Jack; and I do hereby 10
declare that the following is a full, clear, and exact
description of the construction and operation of
the same, reference being had to the annexed
drawings, making a part of this specification,
in which—

Figure 1 is a perspective view, while Fig. 2 is a view of the machine when closed.

In Fig. 1, A A are the top rails; B B, the 15
bottom rails; C C C C, the posts or upright
standards; D, the brace which holds the
machine in place when in an upright position;
E E E E, the rods which hold the machine to- 20
gether with loose joints in C C C C. F is the
rod or handle used in operating the machine;
or they can be operated without the rod F,
using the ends of the rails A A. G is the 25
guide by which brace D is kept in its place,
and acts as a catch for notch H to hold the
machine when in use; I I, slots in C C, by
which the forward end of the bars A A can
drop down, so as to take the forward and hind 30
wheels of the carriage the same height from the
ground or floor, and will allow the rods to rise,
so as to permit the machine to close up, as in
Fig. 2, when not in use. J J are braces to
make the machine more solid and firm when 35
in use.

The machine is constructed of wood, or wood 40
and iron, as should best suit the fancy of the
builder.

The machine is to be used whenever it is de- 45
sired to raise a carriage for the purpose of
washing, greasing, painting, or for raising the
wheels from the ground or floor for any pur- 50
pose whatever.

The machine is to be used by placing it under 55
the vehicle, keeping the rod or handles F to the
hind end of the carriage, placing the rods in 60
the bottom bars, B B, about equal distances
from the forward and hind axle-trees of the
carriage; then taking hold of the rod or handles
F with your hand, holding the machine in its
place with your foot, and pulling toward you, 65
thereby raising the bars A A until the notch
H in the brace D falls onto the catch of guide
G, when you have the vehicle or carriage raised
from the floor or ground.

I claim—

1. The combination of bars B B, arms C C 70
and bars A A, all pivotally attached to
each other, and with lever D and bar G, or
other suitable mechanism adapted for locking
the jack in a hoisted position, said locking 75
mechanism being an independent device from
the hoisting mechanism, substantially as and
for the purposes specified.

2. A wagon-jack consisting of bars B, arms 80
C, the two latter of which have elongated piv- 85
tal bearings, and bars A, of greater length
than bars B, all pivotally connected together
by rods E, locking-lever D H, bar G, and braces
J, all substantially as described.

ALBERT H. TAFT.
